UNITED STATES PATENT OFFICE.

BROOKE ANDERSON, OF HIGHLAND PARK, ILLINOIS.

ANCHOR-PLATE FOR FENCEPOSTS.

1,360,350.

Specification of Letters Patent. Patented Nov. 30, 1920.

Application filed May 5, 1919. Serial No. 294,887.

To all whom it may concern:

Be it known that I, BROOKE ANDERSON, a citizen of the United States, residing at Highland Park, in the county of Lake and State of Illinois, have invented certain new and useful Improvements in Anchor-Plate for Fenceposts, of which the following is a specification.

This invention has for its object the provision of a device of the class named which shall be of improved construction and operation.

The invention is exemplified in the combination and arrangement of parts shown in the accompanying drawing and described in the following specification, and it is more particularly pointed out in the appended claims.

In the drawing—

Figure 1 is a side elevation of a fence post to which one embodiment of the present invention is applied;

Fig. 2 is a view looking from the left in Fig. 1;

Fig. 3 is a section on line 3—3 of Fig. 1; and

Fig. 4 shows a modification of the anchor plate.

Although the present invention is applicable to various forms of fence posts, it is shown in the drawing as attached to a steel angle bar post, such as are placed in the ground by driving. The post is provided with two flanges 10 and 11 which make up the angle bar, one of the flanges being pierced by a number of holes 12 by which the wires are secured to the post. The flange 10 to which the wires are preferably fastened extends in the direction of the plane of the fence when the post is in position in the ground. The bottom end of the post is pointed, as shown at 13, to facilitate driving. Secured to the flange 10 by rivets 14 is an anchor plate 15, preferably made of sheet metal, and located intermediate the lower end of the post and the portion of the post which is positioned at the ground line, when the post is set. It will be seen that the plate 15 is attached to the flange 10 so that it will extend in the direction of the plane of the fence. The plate is substantially triangular in shape with one pointed end extending downwardly so that it will enter readily into the ground as the post is being driven. The position of the plate relative to the direction of the fencing

enables it to resist lateral movement occasioned by pressure against the fence. The post ordinarily is not subjected to pressure longitudinally of the fence for the reason that the wires are free to slide in their fastenings on the post, and any pressure brought upon the fence is transverse to the plane thereof. The plate is preferably positioned below the ground line so that the earth will form a cushion above the plate. In this way the resiliency of the post permits slight yielding under lateral pressure on the fence, and since the post is not held fixed at the ground line there is not so much danger of producing a permanent bend in the post at this point.

It will be seen from the drawing that the plate 15 is provided with ribs 16 struck up from the metal of the plate and arranged in the form of a wide V the arms of which extend downwardly and inwardly from the extreme lateral portions of the plate. The rib 16 has several functions, probably the most important of which is to strengthen the plate against transverse bending. If a flat plate were used it will be apparent that the projecting portions would easily bend laterally against the edges of the flange 10 to which the plate is secured. This bending might take place in shipping the posts, and it is also liable to occur when a heavy lateral strain is brought upon the fence after the post is in place, thus permitting the post to be moved transversely in the earth. Where strengthening ribs 16 are used such lateral bending of the projecting portions of the post is prevented, and the plate may be made of lighter weight material than would be otherwise necessary. The ribs 16 also tend to resist upward movement of the post after the earth has become packed against the plate. The fact that the rib is struck outwardly from the plate produces not only a projection on one side of the plate, but a depression on the opposite side so that on one side of the plate the earth will become packed into the depression to resist upward movement of the post, and on the opposite side of the plate it will become packed about the projecting rib, and thus a double resistance toward upward movement will be produced. The V form of the rib permits the plate to be driven more readily into the ground, and also makes it possible to extend the rib to the extreme lateral portions of the plate without

its crossing the upper central portion of the plate which is left free for the insertion of the holding rivet 14.

In the modification shown in Fig. 4, the 5 two arms of the strengthening rib are terminated inwardly to leave a portion of the plate flat adjacent the post. In some cases this arrangement makes it more convenient to secure the upper rivet 14 in place.

10 I claim:—

1. In combination, a post and an anchor plate secured thereto, said plate having a strengthening rib struck up thereon and the longitudinal axis thereof extending transversely of said post and in a direction inclined to the horizontal.

2. In combination, a fence post and an anchoring device secured thereto, said anchoring device comprising a flat plate attached to said post and provided with a substantially V-shaped strengthening rib formed thereon and having the arms thereof of extending transversely of said post.

3. In combination, a fence post having a flange thereon against which fencing is secured, and an anchor plate secured to said flange and arranged to extend in the direction of the plane thereof, said plate having strengthening ribs formed thereon and extending transversely of said post and across the edge of said flange so as to resist bending of said plate in a direction transverse to the plane thereof.

4. In combination, a fence post and an anchor plate secured thereto, said plate having a strengthening rib formed thereon by a corrugation in said plate so that said rib extends outwardly from the plane of said plate on one side thereof producing a groove or depression on the side of said plate opposite said rib, said rib being arranged to extend across the line of contact between said post and plate.

5. In combination, a post and an anchor plate secured thereto, said plate having a strengthening rib formed thereon and extending transversely of said post, said rib comprising a corrugation formed in the material of said plate so that said rib extends outwardly from the plane of said plate on one side leaving a depression on the opposite side of said plate, said plate being

secured to said post with the side thereof having the depression therein lying against said post.

6. In combination, a fence post and an anchor plate secured thereto, said plate being triangular in shape and having one corner thereof extending downwardly and strengthening ribs formed on said plate and having the longitudinal axes thereof extending inwardly and downwardly from the upper corners of said plate.

7. In combination, a post and an anchor plate secured thereto, said plate being provided with strengthening ribs having their longitudinal axes extending inwardly and downwardly from opposite sides of said plate, and means for securing said plate to said post at a point within the angle formed by said strengthening ribs.

8. In combination, an angle bar fence post having one flange thereof provided with openings for securing fencing thereto and having one end thereof sharpened to permit said post to be driven into the earth, an anchor plate secured to said post between the ground line and the lower end thereof and lying against the face of the flange provided with said securing openings, a strengthening rib formed on said plate and comprising corrugations projecting laterally from the face of said plate so as to leave depressions on the side of said plate adjacent said post, said corrugations being arranged to extend inwardly and downwardly from opposite portions of said plate and across the edges of said flange to which said plate is secured, and an attaching member positioned within the angle formed by said corrugations for securing said plate to said post.

9. In combination, a post and a triangularly-shaped anchor plate secured thereto with one apex of said triangle lowermost, said plate having a V-shaped strengthening rib formed thereon with the arms of said V extending inwardly and downwardly from the upper corners of said triangular plate.

In testimony whereof I have signed my name to this specification on this 2nd day of May, A. D. 1919.

BROOKE ANDERSON.
